UNITED STATES PATENT OFFICE.

WILLIAM O. WEBBER, OF BOSTON, MASSACHUSETTS, ASSIGNOR TO THE
BELL PURE AIR & COOLING CO., OF NEW YORK, N. Y.

FAN-BLADE.

SPECIFICATION forming part of Letters Patent No. 752,275, dated February 16, 1904.

Application filed February 27, 1902. Serial No. 95,880. (No model.)

To all whom it may concern:

Be it known that I, WILLIAM OLIVER WEBBER, a citizen of the United States, residing at Boston, county of Suffolk, and State of Massachusetts, have invented certain new and useful Improvements in Fan-Blades, of which the following is a specification, reference being made to the accompanying drawings, in which—

10. Figure 1 is a plan view of a blade involving my invention, and Fig. 2 is an edge view thereof.

This invention relates to an improved form of fan-blade in connection with centrifugal fan-blowers; and the object of this invention is to produce an improved form of blade which will result in handling the greatest amount of air with the least amount of power, consequently resulting in a greater efficiency of operation. The difference in this form of blade over those heretofore employed is that it is made up of a series of contiguous plane surfaces which are tangential to any desired but definite form of curve and are arranged seriatim along such curve, each being a tangent to the curve at the point thereon where it is placed. I do not desire to limit myself to any specific form of curve, but may adopt an ellipse, a parabola, a circle, or any other form 30 or combination of forms of curve to which the successive plane surfaces may be tangent.

Referring to the accompanying drawings, A represents my improved blade, which, as appears in the drawings, is composed of a series of plane surfaces *a*, *b*, *c*, *d*, and *e*, arranged successively along the curve C and tangent thereto at successive points. The blade thus constructed is attached to the spoke B of the fan, it being understood, however, that blades of this form may be applied to or embodied in a fan structure in any of the well-known ways and that any desired number of them

may be employed. The blade is also shown as of a lesser width at the tip than at the base.

Careful experiments have demonstrated 45 that a fan-blade in a fan-blower, consisting of a series of three or more plane surfaces thus disposed to form consecutive tangents to any well-known and definite form of curve, will handle a larger amount of air with a less consumption of power than blades whose surfaces or working faces are of a strictly curved form—that is, a bending or inflection without angles—thereby producing a marked increase 50 in the efficiency of centrifugal fans and producing a greater economical effect.

The form of blade which I claim also produces a greater stiffness in the blades, the different plane surfaces supporting and stiffening each other, thus rendering them less liable 60 to vibration, and consequently producing a more noiseless fan.

What I claim as new, and desire to secure by Letters Patent, is—

1. A curved fan-blade for centrifugal blowers, said blade having its working face composed of a series of flat surfaces arranged successively on the blade toward its outer end, and said surfaces forming tangents to the curve of the blade. 65

2. A curved fan-blade for centrifugal blowers, said blade having a working face that is narrower toward the outer end of the blade than toward its inner end, said working face comprising a series of flat surfaces arranged successively on the blade toward its outer end. 70

In witness whereof I have hereunto set my hand, before two subscribing witnesses, this 21st day of February, 1901.

WILLIAM O. WEBBER.
